2 Sheets-Sheet 2

UNITED STATES PATENT OFFICE.

JAMES M. COOK, OF ANAHEIM, AND JOHN REEDER GARDINER, OF FULLERTON, CALIFORNIA; SAID GARDINER ASSIGNOR TO SAID COOK.

RIDGING AND BLOCKING MACHINE.

Application filed October 4, 1922. Serial No. 592,334.

This invention has to do, generally, with devices or machines of that general character set forth in United States Letters Patent No. 1,270,597, issued to James M. Cook 5 June 25, 1918, and entitled "Corner finishers for irrigation"; in United States Letters Patent No. 1,279,273, issued to James M. Cook September 17, 1918, and entitled "Dumping scraper attachments for ridges, 10 etc.," and in the copending application of James M. Cook entitled "Dumping scraper", filed July 21, 1921, Serial Number 486,382, and it is an object of this invention to provide a simple effective, improved machine 15 of this general character.

Machines such as are the subject of the above mentioned patents, and copending application, are useful in forming irrigation ridges and ditches, and the like. It is desirable that machines of this character be 20 simple and inexpensive of construction and operation; that they be compact, and that they be comparatively light, as they are used in orchards, and the like, where there are 25 trees or other objects, and are usually drawn by tractors and are operated by the operators of the tractors.

It is an object of this invention to provide a ridging and blocking machine of the character above specified which is extremely simple, compact, light, and convenient to operate, and is, therefore, inexpensive to manufacture, convenient for use in orchards, or the like; easily drawn, and capable of being 35 accurately and conveniently operated.

Another object of this invention is to arrange and form the stationary and movable scrapers of a machine of this character so that they are particularly effective in forming 40 clean ditches and an effective high ridge.

It is another object of this invention to provide an improved simple form of means for releasably holding a movable scraper in operative position.

Further, it is an object of this invention to provide a simple, effective, improved form and construction of dumping, or rotating, 45 scraper device for use in machines of the character above specified, or in like machines.

The objects and features of our invention will be best, and more fully understood by

reference to the following detailed description of a typical preferred form of the invention throughout which reference is had to 55 the accompanying drawings, while its scope will be more particularly pointed out in the appended claims. In the drawings—

Fig. 1 is a plan view of the machine embodying the present invention; 60

Fig. 2 is a side elevation of the machine shown in Fig. 1;

Fig. 3 is a somewhat enlarged detailed sectional view through one of the dumping scrapers, being a view taken as indicated by 65 line 3—3 on Fig. 1;

Fig. 4 is an enlarged sectional view taken as indicated by line 4—4 on Fig. 1:

Fig. 5 is an enlarged plan view taken as indicated by line 5—5 on Fig. 4; 70

Fig. 6 is an enlarged view similar to a portion of Fig. 4, showing the control lever in released position, and

Fig. 7 is an enlarged detailed sectional view taken as indicated by line 7—7 on 75 Fig. 4.

In the drawings numerals 10 designate two stationary scrapers arranged at opposite sides of the machine so that they extend rearwardly and inwardly to form a V, open 80 at its inner end. The scrapers 10 are preferably flat metal scrapers vertically disposed and proportioned and related substantially, as we have illustrated in the drawings. Suitable shoes or blades 10^a are preferably 85 provided at the lower edges of the scrapers 10. The forward ends of the scrapers 10 are connected and spaced by a forward transverse frame part 11, while the rear end portions of the scrapers are spaced and connected by a rear transverse frame part 12.

According to the preferred form of the invention the rear ends of the scrapers 10 are connected by a suitable strap 13. The scrapers 10 are connected with the frame members 11 and 12 by means of suitable straps 14, secured to the scrapers and formed with lugs 15 which extend upwardly through the frame members and have nuts 16 screw-threaded on their upper ends. 90

The structure formed by the scrapers 10 and the frame members 11 and 12 is braced and held rigid by brace parts 17, which extend diagonally between the frame members 95 100

11 and 12. In accordance with the present invention the rear or inner ends of the scrapers 10 are bevelled off, so that the upper rear end portions of the scrapers overhang or extend rearwardly and inwardly beyond the lower rear end portions. (See Fig. 4). By forming the rear ends of the scrapers 10 in this manner they operate to deposit dirt, or the like, caught by the scrapers 10 in a high effective ridge 10

The dumping scrapers 17^A are arranged in combination with the stationary scrapers 10 so that they extend beyond the scrapers 10 and therefore operate to widen the ditches 15 formed by the scrapers 10 and so that they can be operated to form blockades across the ditches formed by the scrapers 10. There is one dumping scraper 17^A arranged to the rear of each of the scrapers 10. Each of the 20 dumping scrapers 17^A comprises a plurality of scraper blades 18 rotatably carried on a shaft 19. In accordance with the present invention the blades 18 are secured to a sleeve 20, preferably a pipe, rotatably carried on the shaft 19, which is stationary. 25

The shaft 19 is supported at the inner ends of the scraper 17^A by brackets 21 attached to the scrapers 10 and is supported at the outer ends of the scrapers 17^A by arms 22 30 extending rearwardly from the outer ends of the rear frame member 12. In accordance with the present invention the brackets 21 and arms 22 carry the shaft 19 close to the rear ends of the scrapers 10 and the shaft 35 19 is formed with an off-set part 25 between the brackets 21 which rigidly connects the two scraper carrying portions of the shaft and allows the shaft to be adjusted relative to the rear ends of the scrapers 10 without 40 interference with the scrapers or with the strap 13 which connects the rear ends of the scrapers 10. In order to allow for adjustment of the shaft 19 relative to the rear ends of the scrapers 10 we adjustably mount the brackets 21 on the scrapers 10 and adjustably 45 mount the arms 22 on the frame member 12. Each bracket 21 is mounted on its scraper 10 by means of a pivot bolt 28 and a clamping bolt 29 which extend through a suitable 50 slot 30 in the scraper. Each of the arms 22 is connected with the frame member 12 by means of suitable bolts 31 and may be adjusted relative to the frame 12 by changing the position of, or by removing, a wedge 32 55 arranged between it and the frame member 12.

In accordance with the preferred form of the invention each of the dumping scrapers 17^A includes two scraper blades 18 arranged 60 diametrically opposite each other and faced in opposite directions so that they will both face forward when in the down, or lower, position. The blades 18 are secured to the sleeve 20 by means of two pairs of straps 35, 65 one located at each end of the scraper. The

straps 35 of each pair are secured to the rear sides of the blades and are formed with inner ends which embrace the sleeve 20 and overlap each other. The overlapping inner end portions of the straps are bolted together so that they tie the two blades together and clamp them solidly onto the sleeve 20. With this construction the sleeve 20, which, of course, is subject to more or less wear, may be readily removed and replaced by simply 70 loosening the clamping bolts in connection with the straps 35. 75

The outer edge of each scraper blade 18 is provided with a cutting member or shoe 36. In accordance with the present invention the inner ends of the scraper blades 18 are cut diagonally, or bevelled off, so that the inner edge portions of the blades, that is, the portions of the blades adjacent the sleeve 20, extend beyond the outer edge portions of the blades. The inner ends of the scraper blades 18, when formed in this manner and properly arranged with relation to the rear ends of the scrapers 10, will cooperate with the scrapers 10, and will feed or force dirt caught by the scraper 17^A to the side of the ridge formed by the scrapers 10. The scraper 17^A is preferably related to the scraper 10 so that the opening between the inner end of the scraper 17^A and the rear end of the scraper 10 is such that the dirt overflowing from the inner end of the scraper 17^A is deposited on the ridge in an even or uniform layer. At the outer end of each scraper blade 18 there is a forwardly 90 extending wing 40. The wings 40 may be advantageously attached to the straps 35 at the outer ends of the scraper blades 18. Further, at the outer end of each of the dumping scrapers 17^A we provide a stationary side 95 or guard plate 50. We have found it convenient to mount the guard plates 50 on the arms 22. In accordance with the present invention the guard plates 50 extend a considerable distance forward of the dumping scrapers 17^A and extend rearwardly to, or 100 preferably a little past the centers of the scrapers 17^A. The guard plates 50 cooperate with the wings 40 in preventing excess dirt, or the like, caught by the scrapers from overflowing or discharging from the outer ends of the scrapers and cause the excess dirt to 105 discharge from the inner ends of the scrapers at the ridge. 110

In accordance with the present invention there is an independent releasably controlled means for each of the dumping scrapers. Each means includes a strap 55 in connection with each of the scraper blades 18, a stop 58 on each of the straps, and a trip mechanism adapted to cooperate with the stops. Each strap is arranged at the rear of the blade in connection with which it is arranged and has a straight part 55^A extending radially from the sleeve 20 at substantially right 115 120 angles. The trip mechanism is arranged to 125 move the strap 55 so that the straight part 55^A is moved from the rear of the blade to the front of the blade. The stop 58 is arranged to 130

angles to the plane of the blades, a curved part 60 which extends from the outer portion of the straight part 55^a toward the blade in connection with which the strap is arranged, and a straight part 61 which connects the outer end of the curved part 60 with the said blade. The inner ends of the straight parts 55^a preferably embrace the sleeve 20 and overlap, as we have clearly illustrated in the drawings, while the curved parts are preferably concentric with the shaft 19. The stops 58 are removably mounted on the outer ends of the parts 55^a and project somewhat beyond the outermost parts of the dumping scraper.

The trip mechanism 56 includes a shaft 70 having an operating arm or lever 71 at one end and a crank 72 at the other end. Shaft 70 is carried by suitable brackets 73 mounted on the frame member 12. The crank 72 carries a suitable roller 74 and is proportioned so that it can be positioned to engage and hold either of the stops 58. The crank is designed so that it can be actuated by rotation of the shaft 70 so that it is out of position to cooperate with the stops 58. By providing the crank 72 at one end of the shaft 70 the roller 74 can be very easily and conveniently arranged on and removed from the crank for purpose of repair or replacement. The operating lever 71 is preferably formed integral with the shaft 70 and is adapted to be swung between the positions shown in Figs. 4 and 6 for the purpose of rotating the shaft and moving the crank 72 between the two positions above described. In accordance with the present invention a bracket 76 is adjustably mounted on the frame 12, preferably over one of the brackets 73. The bracket 76 is formed with a finger 77 which extends beyond the lever 71 to limit its rearward movement and thus determine its rear position. When the lever 71 is in the rear position, as illustrated in Fig. 4, the crank 72 is in position where the roller 74 will cooperate with either of the stops 58. By adjusting the plate 76 the rear position of the lever 71 can be adjusted and thereby change the position of the crank 72 so that it will operate to hold the scraper in a different rotative position. Although the lever 71 may be operated in various manners it is usually operated by a jerk line attached to its outer end.

In accordance with the present invention a single spring 90 is arranged in connection with the lever 71 to hold it in either the position shown in Fig. 4 or that shown in Fig. 6. Spring 90 is preferably a helical spring having one end connected with the lever 71 and the other end connected with a bracket 91, which is mounted on the frame member 12. The parts just described are designed and proportioned so that movement of the lever 71 between the position shown in Fig.

4 and that shown in Fig. 6, causes the spring to throw over or past the center of the shaft 70 so that it tends to move the lever 71 rearwardly when the lever is in the position illustrated in Fig. 4, and tends to move the lever 71 forwardly when the lever is in the position as illustrated in Fig. 6.

In accordance with the preferred form of construction we arrange a shaft 94 transversely of the machine, preferably a little to the rear of the center of gravity of the machine, and form the shaft 94 at the outer side of each of the scrapers 10 with a crank arm 95 on which is mounted a supporting wheel 96. In the particular form of machine illustrated in the drawings the shafts 94 are carried by bearings 97 mounted on the scrapers 10. The crank arms 95 are proportioned so that they can be swung to a position where the wheels 96 are spaced somewhat above the lower edges of the scrapers 10 or to a position where the wheels 96 extend somewhat below the lower edges of the scrapers 10 to support the machine. For the purpose of rotating the shaft 94 to swing the crank arms 95 between the positions just described we secure an operating lever 98 on the shaft 94. Further, we provide releasable means for setting the lever 98 against movement so that the crank arms 95 may be set in the desired position.

In the particular form of construction illustrated in the drawings the means just described for setting the lever 98 against movement includes a stationary notched segment 98', pawl 99 carried by the lever 98 to cooperate with the notched segment, and an operating lever 100 for the pawl 99 located at the handle end of the lever 98.

In operation the machine is drawn, as by horses or a tractor, or the like, so that the scrapers 10 form two spaced ditches and deliver the soil from the ditches into a single high ridge between the ditches. When the machine is drawn by horses the operator may ride on the machine and a suitable operating mechanism—say a foot lever, etc.,—may be connected with the releasable control means hereinabove described through suitable rods, or the like. When the machine is drawn by another machine, say, for instance, a tractor, the levers 71 of the control mechanisms may be operated from the tractor by jerk lines. The levers may be released by pulling on the jerk lines and may be thrown into operating position by whipping the jerk lines in the proper manner. The dumping scrapers are held by the means hereinabove described so that they are inclined somewhat upwardly and rearwardly and operate to widen the ditches formed by the scrapers 10 and to hold and carry the dirt which they remove in widening the ditches. Excess dirt caught by the scrapers 17^a passes to their inner ends and is delivered onto the

sides of the ridge as hereinabove described. When it is desired to form a blockade across one of the ditches the dumping scraper operating in that ditch is released so that it 5 rotates, due to the forward movement of the machine, and dumps the dirt carried by it. As the dumping scraper rotates to dump the dirt carried by it it is supported or carried over by the dirt it is dumping until the 10 strap 55, which has been in operation to hold it in operative position, comes into position to support it until it has made a half revolution at which time it has completely discharged its load and is again in operative 15 position. In passing over the load of dirt in this manner the scraper 17^A packs it so that it forms an effective blockade. In practice, after the dumping scraper has been released the control means is immediately 20 thrown so that it will catch and hold the scraper after it has made half a revolution. The formation and arrangement of the straps 55 is particularly important in that they do not in any way interfere with the 25 dirt which is caught and carried by the scraper and yet are of sufficient extent and are so located as to carry the scraper around into the desired operative position after the load has carried it around during the first 30 part of its rotation. In other words, the straps are not of such extent as to cut or break the blockade formed by the scrapers but do operate to effectively carry the scrapers after the dirt has been dumped. 35 Having described only a preferred form of our invention we do not wish to limit ourselves to the particular details hereinabove set forth but wish to reserve to ourselves any changes, modifications or variations 40 that may appear to those skilled in the art and fall within the scope of the following claims.

Having described a preferred form of our invention, we claim:

- 45 1. In an earth ridging and blocking machine a rotary scraper including a blade having its outer end straight and its inner end beveled off.
- 50 2. In a machine of the character described, a diagonally arranged stationary scraper, and a transversely arranged scraper arranged behind the stationary scraper, the rear end of the stationary scraper and the inner end of the dumping scraper being 55 diagonally disposed so that they cooperate to form an upwardly and inwardly extending opening through which material can discharge from the dumping scraper.
- 60 3. In a machine of the character described, a diagonally arranged stationary scraper, a frame member in connection with the stationary scraper, a dumping scraper, means mounting the dumping scraper behind the stationary scraper including an arm extending 65 from the frame member and supporting

the outer end of the dumping scraper, and a plate carried by the arm at the outer end of the dumping scraper and so that it extends forward of the dumping scraper.

4. In a machine of the character described, 70 a scraper adapted to be rotatably carried on a shaft including, a sleeve, two blades extending radially from the sleeve, and straps connected to the rear sides of the blades the inner ends of the straps connected 75 with the two blades being overlapped around the sleeve and clamped together on the sleeve.

5. In a machine of the character described 80 a rotating scraper including two spaced blades extending from the axis of the scraper, and a part extending from the outer part of one of the blades curved concentrically with the axis of the scraper and extending only a portion of the way between the blades. 85

6. In a machine of the character described, 90 a rotating scraper including two blades extending radially in opposite directions from the axis of the scraper, and two diametrically opposite members at the outer parts of the 95 blades curved concentrically with the axis of the scraper, each member extending from the front of one of the blades only a portion of the way to the other blade.

7. In a machine of the character described, 95 a rotating scraper including two blades extending radially in opposite directions from the axis of the scraper, two diametrically opposite members at the outer parts of the 100 blades curved concentrically with the axis of the scraper, each member extending from the rear of one of the blades only a portion of the way to the other blade, and parts connecting the outer ends of the members with the center of the scraper. 105

8. In a machine of the character described, 110 a rotating scraper including two blades extending radially in opposite directions from the axis of the scraper, two diametrically opposite members curved concentrically with the 115 axis of the scraper, each member extending from the rear of one of the blades only a portion of the way to the other blade, and means for controlling rotation of the scraper including, stops carried by said members, and a relatively stationary releasable catch mechanism adapted to cooperate with the stops.

9. In a machine of the character described, 120 a diagonally arranged stationary scraper, a transversely arranged dumping scraper arranged behind the stationary scraper, the rear end of the stationary scraper and the inner end of the dumping scraper cooperating 125 to form an upwardly and inwardly extending opening through which material can discharge from the dumping scraper, and a stationary plate at the outer end of the dumping scraper extending forward therefrom. 130

10. In a machine of the character described, a dumping scraper, and control means for the scraper including, a part movable into and out of engagement with the 5 scraper, an operating lever for said part movable between two positions, one in which the part is in position to engage the scraper and the other in which the part is out of

position to engage the scraper, and means for yieldingly holding the lever in said positions. 10

In witness that we claim the foregoing we have hereunto subscribed our names this 25th day of September 1922.

JAMES M. COOK.

JOHN REEDER GARDINER.
